US0D1013968S

(12) **United States Design Patent** (10) Patent No.: **US D1,013,968 S**
(45) Date of Patent: ** Feb. 6, 2024

(54) **RESCUE EQUIPMENT**

(71) Applicant: **Nanjing Kaitianyan UAV Technology Co. LTD**, Nanjing (CN)

(72) Inventors: **Chong Chen**, Jiangsu (CN); **Xiaoyu Shi**, Jiangsu (CN)

(**) Term: **15 Years**

(21) Appl. No.: **35/515,194**

(22) Filed: **Aug. 30, 2022**

(80) **Hague Agreement Data**

Int. Filing Date: **Aug. 30, 2022**

Int. Reg. No.: **DM/223480**

Int. Reg. Date: **Aug. 30, 2022**

Int. Reg. Pub. Date: **Sep. 23, 2022**

(51) **LOC (14) Cl.** 02-99
(52) **U.S. Cl.**

USPC **D29/124**; D12/16.1; D21/444

(57) **CLAIM**

The ornamental design for a rescue equipment, as shown and described.

DESCRIPTION

1.1 is a perspective view of the rescue equipment;

1.2 is a front view thereof;

1.3 is a back view thereof;

1.4 is a top view thereof;

1.5 is a bottom view thereof;

1.6 is a left view thereof;

1.7 is a right view thereof.

1 Claim, 7 Drawing Sheets
